UNITED STATES PATENT OFFICE.

ADOLPH BAYER, OF BROOKLYN, NEW YORK.

DESIGN FOR A THERMOMETER.

SPECIFICATION forming part of Design No. 24,588, dated August 13, 1895.

Application filed June 27, 1895. Serial No. 554,271. Term of patent 14 years.

To all whom it may concern:

Be it known that I, ADOLPH BAYER, a citizen of the United States, residing at Brooklyn, in the county of Kings and State of New York, have invented and produced a new and original Design for Thermometers, of which the following is a specification, reference being had to the accompanying drawing.

The object of this design is to provide a handsome and ornamental thermometer tube or stem which presents a characteristic and distinguishing appearance to the eye.

The design consists in a thermometer tube or stem which is ornamented at one end by a sphere.

The design is illustrated by the accompanying drawing, which shows an elevation of a thermometer.

In the drawing, the numeral 1 indicates the thermometer tube or stem. 2 is the bulb, and 3 is the ornamental sphere at one end of the tube or stem.

The design provides an ornamental, handsome, and distinctive thermometer.

What I claim as new, and desire to secure by Letters Patent, is—

The design for a thermometer, substantially as shown and described.

In testimony whereof I have hereunto set my hand in the presence of two subscribing witnesses.

ADOLPH BAYER.

Witnesses:

WM. C. HAUFF,
E. F. KASTENHUBER.
